UNITED STATES PATENT OFFICE.

REINHOLD SCHOELL, OF STAMFORD, CONNECTICUT, ASSIGNOR TO THE YALE & TOWNE MANUFACTURING COMPANY, OF STAMFORD, CONNECTICUT.

LOCK.

1,420,760.

Specification of Letters Patent. Patented June 27, 1922.

Application filed August 4, 1920. Serial No. 401,194.

To all whom it may concern:

Be it known that I, REINHOLD SCHOELL, a citizen of the United States, and a resident of Stamford, in the county of Fairfield and State of Connecticut, have invented certain new and useful Improvements in Locks; and I do hereby declare the following to be a full, clear, and exact description of the invention, such as will enable others skilled in the art to which it appertains to make and use the same.

My invention relates to an improvement in locks, the object being to provide a rim dead lock with means that will so interlock with the keeper as to prevent a separation of the lock and keeper by jimmying or otherwise, sufficiently to release the bolt from the keeper, and it consists in a lock carrying a hasp adapted to engage a keeper and a bolt also engaging the keeper the hasp being actuated by the movements of the bolt.

In the accompanying drawings; Figure 1 is a view in elevation of a part of a door and jamb showing the lock and keeper in place and the door locked; Figure 2 is a view of the door from the opposite side showing the cylinder lock; Figure 3 is a view in rear elevation of the lock the cover plate being removed and showing the bolt and hasp in locking position; Figure 4 is a similar view, the bolt and hasp being in unlocking position; Figure 5 is a view in section on the line C—D of Figure 3; Figure 6 is a view in edge elevation partly in section, the section being taken on the line A—B of Figure 3; Figure 7 is a view in longitudinal section of the lock taken through the center of the bolt; Figure 8 is a view in elevation and Figure 9 an edge view of the bolt; Figure 10 is a view of the hasp detached and Figure 11 is a view of the hasp actuating lever.

The rim latch comprises a cover plate 11 adapted to be secured to the inner side of a door, and a casing 12 secured to the cover plate in the usual and well known manner. Removably secured by screws 13 to the posts 14 projecting from the inner surface 50 of the casing 12, is the plate 15 provided adjacent its rear end with the support 16 to which the hasp operating lever 17, which will be hereinafter referred to, is pivoted at its rear end. The lever extends for-

wardly alongside of one edge of the bolt 18, 55 which latter as shown in Figures 3 and 4, is longer than the usual bolt and is mounted in and projects through both ends of the lock casing. The bolt is provided approximately at its center with a transverse slot 60 19 for the passage of the shank 20 of the knob 21, and the shank carries the arm 21^a provided at its outer free end with the hole to receive the pin 22 on the slide block 23 which latter rests and moves within the 65 dovetailed groove 24 in the guide 25. This guide is secured to the bolt adjacent one edge of the latter, and projects beyond said edge, and the block 23 is provided with a wrist pin 26 which connects it with the bolt 70 actuating plate 27 which latter is engaged by the key mechanism hereinafter referred to. The slide block is also connected to the bolt actuating plate 27 by the pin 22, which as previously explained also passes through 75 a hole in the end of arm or roll-back cam 21^a rigidly secured on the knob shank or spindle 20. It will therefore be seen that the knob spindle has a pivotal connection through arm 21^a with the bolt actuating 80 plate 27, and the latter is connected with the bolt through the medium of the slide block 23 and guide 25. Assuming for the purpose of illustration that the bolt is in its retracted position as shown in Figure 4, 85 and the knob be turned, the bolt actuating plate 27, which is connected with the knob shank 20, acting through the slide block and guide, shifts the bolt to its projected position. As the arm 21^a rises, it lifts the bolt 90 actuating plate to a position above the upward extension 28 on plate 15, and then lowers it to a position in front of said extension, the said bolt actuating plate moving in the arc of a circle. When in its retracted position it is at the rear of the extension 28, and when in its projected position 95 as shown in Figure 3 it rests in front of said extension and to retract the bolt the plate 27 must be moved upwardly to clear 100 such extension, hence with this mechanism, the bolt will be deadlocked in its two positions, and owing to the circular movement of the arm 24, the throw of the bolt is approximately twice the length of the arm 105 21 thus giving it an extra long throw.

Secured to the outer face of bolt actuating plate 27 is the horse shoe shaped plate

27^a, the open end of the latter being downward. Instead however of using an extra plate, plate 27 can be thickened and recessed to form the U-shaped recess therein. 5 This recess is to receive the pin 29 on the cover-roll-back-cam 30 which latter is turned by a key inserted in the cylinder or pin tumbler lock 31 at the outer side of the door.

10 This lock and its connection with the cover-roll-back-cam 30, is of the well known construction and operates in the usual and well known manner, so that when the cam 30 is turned by a key, the lug 29 thereon enters the open end of the recess in plate 27 and actuates the plate, by engagement with the walls of the U-shaped recess to shift the bolt. After the bolt has been shifted by the key mechanism, the continued movement 15 of the key carries the cover-roll-back-cam 30 down to the position shown in Figure 3 and out of the path of movement of the plate 27, thus leaving the latter free to be actuated by the knob 21 or by the key lock.

15 32 is a spring actuated lever pivotally secured to the bolt 18 in advance of the guide 25. This lever is of the bell-crank type and is connected at the end of its shorter arm to the spring 33, the other end of which latter 20 is secured to and carried by the guide block 25, while the free end of the longer arm of said lever rests under the pin 26 on the sliding block 25 and above the free end of arm 21, and tends to complete the throw of the 25 latter both in projecting and retracting the bolt, so that after the pin 22 passes the centre, the tension of the spring acting on the lever throws arm 21 to its horizontal position even if the knob 21^a be released before the completion of the throw.

25 In the operation of the bolt by the knob from the inner side of the door, the arm 21 shifts the sliding block 23, which, acting against the guide 25 shifts the bolt. When 30 the bolt is actuated by the key it is done through the engagement of the cover-roll-back-cam 30 acting on the plate 27. In both instances the bolt is shifted approximately twice the length of the lever arm 21 roll-back-cam 30, that is to say, it shifts it from the position shown in Figure 4, to that shown in Figure 3, consequently it gives to the bolt an extra long throw which with the hasp which will now be described will absolutely 35 prevent any separation of the keeper from the lock by jimmying or otherwise.

35 34 is a hasp pivotally secured at its ends to the upper and lower edges of the lock case adjacent the front edge or face plate of 40 the latter, and adapted when in its locking position to project beyond the lock and overlap the keeper. This hasp is secured to the pintles 35 and 36 journaled in the lock casting, and the pintle 36 terminates in a crank 45 37, the crank pin of which rests in the open front slot of the hasp operating lever 17. This lever, as previously explained is located adjacent one edge of the bolt and the slot 17^a therein receives the pin 38 carried by the bolt 18. The slot 17^a is straight for 70 a point adjacent its front edge backward, and it then curves upwardly and slightly downwardly at its rear end as shown in Figure 5. When the bolt is projected as shown in Figures 3 and 5 the pin 38 rests adjacent 75 the front end of the slot, and when retracted it rests at the rear end thereof. When the bolt is in its retracted position the hasp is turned up and rests over the outer edge of the lock casing, as shown in Figure 4. As the bolt begins to move outwardly either by the actuation of the knob or a key, the pin 38 moving in the rear curved end of the slot shifts the lever in a direction to actuate crank 37 and throw the hasp over to the 80 front of the lock, as shown in Figures 3 and 5, and this movement of the hasp occurs before the bolt has been moved sufficiently to interfere with the movement of the hasp. By the time the bolt has been moved far enough for the pin 38 thereon to enter the straight part of the slot 17^a in the hasp actuating lever, the hasp will have been turned to its locking position so that the continued movement of the bolt will have no 85 effect on it whatsoever. In retraction of the bolt, the pin 39 moving in the straight part of the slot permits the bolt to be withdrawn sufficiently to free, or be out of the path of the hasp before the latter is turned back to 90 its normal interlocking position, which turning movement is effected by the pin 38 entering the curved part of the slot 17^a in the hasp actuating lever. From the above it will be seen that the hasp is turned to its 95 locking position before the bolt is fully projected, and is not restored to its normal position until after the bolt has been partly retracted.

95 In the drawings I have shown a keeper 39 having two parallel strike plates 40 and 41, the latter being separated sufficiently to permit of the easy and free entrance of the hasp 34 between them. The second or outer strike 41 may be dispensed with, but I prefer to use it as it forms a housing for the portion of the bolt projecting over the hasp. 100

100 Both strikes 40 and 41 are slotted to receive the bolt, and the slots are preferably somewhat larger than the bolt so as to 105 provide for shrinkage of the door or jamb without any binding between the bolt and strike plate and the hasp is made longer than the strike plate for the same purpose.

105 The hasp is limited in its outward or locking movements by the pins 42 secured to the lock casing 12, and it is locked against any lost or free movement when in its normal or unlocking position by the hasp locking pin 43. This pin 43 is mounted to 110

110

115

120

125

130

slide in the lock casing, with one rounded end projecting beyond the latter and its other end in engagement with the bolt 18, which latter is provided just at the rear 5 of its free end with a groove 44 located in the plane of the pin 43. The outer rounded projecting end of the pin 43 is adapted to enter the recess 45 in the inner face of the hasp when the bolt is retracted and positively 10 lock the hasp against any swinging or lost motion. As the bolt begins its outward movement, the inner end of the hasp locking pin enters the groove 44 thus leaving the pin free to be moved outwardly by 15 the hasp and the latter free to be turned by the hasp actuating lever 17 as previously explained.

In the operation of the lock, the hasp 34 is thrown to its position embracing the 20 strike 40, before the bolt has passed through the latter and is in a plane below or at the rear of the bolt as the latter emerges from the strike 40 and approaches the strike 41, hence when the bolt is fully projected it 25 is engaged by both strikes, and the hasp is within the keeper at the rear of the bolt and embracing the strike 40, and so secures the lock to the keeper that they cannot be forced apart by a jimmy or other tool, 30 sufficiently to allow the bolt to be disengaged from the keeper, hence when the door is locked the lock can be disengaged from the keepers only by the operation of the knob from the inside of the door or by 35 a key from the outer side.

It is evident that many changes in the construction of the parts may be resorted to without departing from the spirit of my invention which comprehends broadly a 40 hasp engaging a keeper for preventing a separation of the lock and keeper and a bolt also engaging the keeper and overhanging the hasp, the latter being actuated to engage and disengage the keeper by the movement 45 of the bolt.

Having fully described my invention what I claim as new and desire to secure by Letters-Patent, is:—

1. The combination of a keeper, a lock 50 having a bolt adapted to be projected to engage the keeper, means for actuating said bolt and a hasp carried by the lock and adapted to be automatically moved to engage the keeper.

2. The combination of a keeper, a lock having a bolt adapted to be projected to engage the keeper, mechanism for actuating the bolt, and a hasp carried by the lock and movable to engage the keeper, the hasp engaging the keeper at the rear of the bolt so that it will be locked against releasing movement by the bolt.

3. The combination of a keeper having a slot for a bolt, a lock having a bolt to enter 65 the slot in the keeper and a hasp to embrace

the keeper and means connecting the bolt and hasp whereby they are actuated in unison.

4. The combination of a keeper constructed to receive a bolt, a lock having a sliding bolt adapted to enter the keeper and a pivoted hasp to embrace the latter, means connecting the bolt and hasp whereby the latter is actuated by the former and means for holding the hasp against lost motion 70 when in its normal or unlocking position.

5. The combination of a keeper constructed to receive the end of a bolt, a lock having a sliding bolt to enter the keeper and also provided with a pivoted hasp adapted to 80 embrace the keeper, and means for actuating the bolt and keeper whereby the hasp will be moved to its position around the keeper before the bolt is fully seated in the latter so that the hasp will be at the rear 85 of and overlapped by the bolt.

6. The combination of a keeper constructed to receive the end of a bolt, a lock having a sliding bolt to enter the keeper and also provided with a pivoted hasp adapted to 90 embrace the keeper and be overlapped by the bolt, means for actuating the bolt and means actuated by the moving bolt for shifting the hasp.

7. The combination of a keeper constructed to receive the end of a bolt, a lock having a sliding bolt to enter the keeper and also provided with a pivoted hasp to embrace the keeper, means for actuating the bolt, means actuated by the bolt for turning 95 the hasp on its pivots and a pin also actuated by the bolt and engaging the hasp for holding the latter in its normal or unlocking position.

8. In a lock, the combination of a sliding 105 bolt, a guide thereon, a slide movable in the guide and a roll-back-cam adapted to be engaged with and disengaged from said slide and acting on the latter for shifting the bolt.

9. In a lock, the combination of a sliding 110 bolt, a guide thereon, a slide movable in the guide, a roll-back-cam moving in a half circle and engaging the slide whereby the bolt may be projected or retracted by a complete up and down movement of the slide in the 115 guide, and means for actuating the roll-back-cam and also for disengaging it from the slide thus leaving the latter free to be actuated by a knob.

10. In a lock, the combination of a sliding 120 bolt, a guide rigidly secured to said bolt and having a slide way at right angles to the direction of movement of the bolt, an arm adapted to move in a half circle and connected with the slide, and a spring pressed 125 lever adapted to yieldingly hold the slide in its lowest position whereby the final movement of the slide both in projecting and retracting the bolt will be assisted or accomplished by the spring pressed lever.

11. In a lock, the combination of a sliding bolt, a guide secured thereto, a slide mounted in said guide, a stop or abutment, and means for shifting the slide from one side of the said abutment up and over the same to the other side, whereby the said stop or abutment forms a dead lock for the bolt and means connected with said slide for actuating it to shift the bolt.
- 10 12. The combination of a keeper, a lock casing, a bolt, a pivoted hasp, means for operating the bolt and the pivoted hasp whereby they are caused to engage and disengage the keeper, and a sliding pin carried by the lock casing, actuated by the bolt, and engaging the hasp for locking the latter in its normal or unlocking position.
- 20 13. The combination of a keeper having separated strike plates, a lock having a bolt adapted to engage both plates and also having a hasp actuated in unison with the bolt and adapted to embrace one of the strike plates and means for actuating the bolt and hasp.
- 25 14. The combination of a keeper having separated strike plates, a lock having a sliding bolt adapted to engage both strike plates and also having a pivoted hasp adapted to embrace one of the strike plates, means connecting the bolt and hasp whereby they are actuated in unison and means for shifting the bolt.
- 30 15. The combination of a keeper having separated strike plates, both of which are slotted, a lock having a bolt adapted to enter said slots, a hasp pivoted to said bolt and adapted to be moved to a position to embrace one of the strike plates, means connecting the bolt and hasp whereby the hasp will be moved to its position in advance of the completion of the throw of the bolt, so that it will be overlapped by the bolt, and means for actuating the bolt.
16. In a lock, the combination of a sliding bolt, a guide rigidly secured thereto and having a slide way at right angles to the direction of movement of the bolt, a slide in said guide way, one face of said slide being recessed, a knob shank or spindle having an arm connected with said slide, and a key actuated roll-back-cam adapted to engage the recessed face of the slide whereby the latter may be actuated either by a knob from the inside or a key lock from the outside.
17. The combination of a keeper, a lock having a bolt adapted to be projected to engage the keeper, a hasp carried by the lock and adapted to be turned to engage the keeper and means actuated by the bolt for turning the hasp into and out of its locking position.

In testimony whereof, I have signed this specification in the presence of two subscribing witnesses.

REINHOLD SCHOELL.
